UNITED STATES PATENT OFFICE

ALBERT KINDELMANN, OF FLORAL PARK, AND EWALD BOECKING, OF BROOKLYN, NEW YORK, ASSIGNORS TO INTERNATIONAL PROJECTOR CORPORATION, OF NEW YORK, N. Y., A CORPORATION OF DELAWARE

INTERLOCKING SHAFT CONSTRUCTION

Application filed January 6, 1931. Serial No. 506,906.

This invention relates to a simple and efficient means whereby a framing shaft in a motion picture apparatus may be operated either from within the casing when the door 5 is open or from outside the casing when the door is closed.

A main object of the invention is to provide an automatically established connection between the main shaft within the casing and an auxiliary shaft mounted on the door, so that when the door is closed this connection is established and the main shaft can be driven or turned by operating the auxiliary shaft from outside the door. 10

15 A further object provides simple and efficient means whereby this connection can be effected through the use of simple, inexpensive, durable elements, not complicated in construction and arrangement.

20 A further object is to provide a connection which can be automatically established when the door is closed, substantially regardless of the angular position, when the door is closed, of the auxiliary shaft thereon.

25 Further and more specific objects, features and advantages will more clearly appear from a consideration of the specification hereinafter taken in connection with the accompanying drawings which form part of 30 the specification and will illustrate a present preferred form of the invention.

Briefly and generally considered the invention includes a main shaft within a casing, part of which casing comprises a pivoted 35 door which sometimes is swung open, in order that the shaft within the casing can be operated, when desired, without opening the door. An auxiliary shaft is mounted on the door and provided with suitably manually 40 operable means to turn it. The auxiliary shaft extends within the casing and on its end is provided with means for engaging with the main shaft within the casing. This engaging means automatically engaging, as 45 the door closes, substantially regardless of the angular position of the auxiliary shaft and the door as it is closed.

A preferred form of engaging means comprises projecting pins on one shaft and corresponding receiving holes or recesses on the

other. Preferably the pins are on the end of the auxiliary shaft and the holes are disposed on the operating knob on the end of the main shaft within the casing.

The present preferred form of the invention is illustrated in the drawings, of which:

Fig. 1 is a side elevation with certain portions broken away, of the framing handle and shaft construction;

Fig. 2 is a vertical longitudinal section through the construction shown in Fig. 1;

Fig. 3 is a similar section through the right hand end of the construction showing an attachable portion of the shaft in the inoperative position;

Fig. 4 is a transverse section taken on line 4—4 of Fig. 2;

Fig. 5 is a similar section taken on line 5—5 of Fig. 2;

Fig. 6 is a similar section taken on the line 6—6 of Fig. 2; and

Fig. 7 is a similar section taken on line 7—7 of Fig. 2.

As shown in the drawings, the framing shaft construction with the unlocking handle is adapted for use on motion picture apparatus, especially projectors wherein it is desirable to be able to operate the shaft from either side of the machine which has the usual door, to be able to operate the shaft when the door is closed, as well as when it is open. With this main idea in view the construction involves a casing indicated by walls 10 and 11 with a side door wall 12 of a side door. Within the casing is disposed the usual oil box 13 containing the intermittent mechanism, whereby the film is intermittently advanced through the machine. This box in framing the film as well known in the art is adapted to be rotated the desired amount and to that end is provided with peripheral teeth 14 engaging with teeth on a gear 15. This gear is attached to or is formed integral with a sleeve 16, slideable on shaft 17 which is the main framing shaft. This shaft extends from outside the wall 10 through the wall or partition 11 to a point adjacent the inner face of door 12. A

spring 18 bears against the face of the gear 15 at one end and against a lug 19 at the other end, said lug being keyed or otherwise fas-

tened to the shaft 17. The opposite face of the gear has a clutch disk 20 fastened thereto by means of screws 21. This clutch disk having teeth 22 engageable with corresponding teeth 23 on a fixed clutch disk or plate 24 fastened by screws 25 to a plate 26 which in turn is fastened by screws 27 to the wall or partition 11. These clutch disks have central bores through which the sleeve 16 and shaft 17 extend.

10 The plate 26 is provided with a sleeve-like outwardly threaded extension 27' also adapted to receive and act as a bearing for shaft 17. A cup 28 is threaded into the end of this portion 27' and packing 29 is disposed therein. This packing may be oily material to properly lubricate the bearings. The end of the sleeve 16 toward the plate 26 is provided with a transverse notch 30 and a transverse pin 31 on the shaft 17 is adapted to lie in said notch. This engagement permits the shaft 17 when turned to turn the sleeve 16 and consequently the gear 15. This engagement also permits the shaft 17 as it starts to turn as in Fig. 2, to withdraw the clutch disks from engagement so that the gear 15 can be turned. Therefore, the initial movement of the shaft as it is turned will disengage the clutch member by the action between the pin and the shaft 17 riding part way up the bevelled side of the notch 30. After the clutch members are disengaged further turning of the shaft will turn the gear 15 to effect the framing adjustment.

35 The right-hand end of shaft 17 is provided with a cup-like end knob 32 fastened thereto by screw 33. Within the bottom of the cup portion of this knob 32 are provided a series of holes 34 preferably arranged in a circle. 40 Fastened by screw 35 to door wall 12 is a plate 36 having a sleeve 37 thereon extending through a bore 38 in the door. This sleeve acts as a journal for an auxiliary shaft 39, the outer end of which is provided with an 45 end knob 40 outside the door, on the inner end of which is provided a plate 41 having outwardly extending pins 42 thereon which are adapted to extend into the holes 34 above-mentioned. When the door is open, as shown 50 in Fig. 3, the pins are withdrawn from the holes, but in this case the end knob 32 within the casing can be operated to move the shaft 17. When the door is closed the pins 42 enter the holes 34 thus permitting the turning of 55 knob 43 from outside the door to operate the shaft 17. In this manner, therefore, the framing shaft can be operated whether the door is open or closed, and the proper connection for operating it from without the casing 60 is automatically made as the door is closed.

The left end of shaft 17 is journalled in a hub 43 on wall or portion 10 and is provided with a suitable packing material 44 held in place by plate 45. The end knob 46 is dis-

posed on this end of shaft 17. This knob is provided with a slot 47 to receive a screw 48 fastened to the shaft 17. This end of the shaft has on it a nut 49 between the inner shoulder of which and the adjacent face of the knob 46 is disposed a spring 50. Between the end face of the knob 46 and the plate 45 is disposed a washer 51. Adjacent the inner end of hub 43 there is disposed a collar 52 fastened to shaft 17 by a pin 53.

In the operation of the device it will be assumed that the parts are in the position shown in Fig. 2, with the door 12 closed. In this position the two clutch disks 20 and 24 are engaged and, therefore, the gear 15 can not be turned by turning the shaft 17. If it is desired to operate the shaft 17 from outside the door 12, when the door is closed then the knob 40 is turned the desired amount. With the door closed the pins 42 engage in the holes 34 and turning of knob 40 is thereby effective to turn the shaft 17. As shaft 17 starts to turn the pin 31 will coat with the bevelled sleeves of the notch 30 and slide the sleeve 16 to the left against the action of the spring and disengage the clutch, further movement of the shaft will turn the gear 15. After the desired movement for framing is achieved, the hand of the operator is taken off the shaft, this will permit the spring 18 to move the sleeve and clutch member into engagement and restore the normal cooperative relation between the pin 31 and the notch 30.

If it is desired to open the door 12 it is 100 swung open as shown in Fig. 3, and operation of shaft 17, when the door is open is effected in a similar manner, by turning the knob 32, whereupon the action takes place.

If it is desired to operate the same from the left-hand side of the projector casing from 105 outside the partition 10, then the knob 46 is turned whereupon the action takes place as above described.

This device, therefore, permits a shaft to be operated from a plurality of points by 110 providing an auxiliary section or shaft which can be moved to interlocking position with the main shaft, when desired. The main shaft and the auxiliary shaft are each provided with means for turning them. The main shaft, therefore, can be turned either directly from one or two points, or can be turned through co-operation with the auxiliary shaft from an additional point. In the present preferred form operation of a framing shaft disposed within a casing can be 115 operated from either side of the casing and outside of it or from within the casing when the door is open. In other instances, the simple turning of the shaft will release the latching clutch members and further movement of the shaft will effect the desired adjustment within the casing. This connection, of course, can be used in various ways 120 and is adapted to be operated from any one 125

of several points, but is especially useful where the shaft is used within a casing and should be operated from either within or without the same. This action can take place whether the elements are pivoted or mounted longitudinally. The door on which the auxiliary shaft is mounted may be pivoted as shown or may be otherwise mounted for direct longitudinal movement.

10 While the invention has been described in detail and with respect to a present preferred form thereof, it is not to be limited to such details and forms since many changes and modifications may be made in the invention 15 without departing from the spirit and scope of the invention in its broadest aspects. Hence it is desired to cover any and all forms and modifications of the invention which may come within the language or scope of 20 any one or more of the appended claims.

What is claimed, is:

1. In combination a shaft within a casing, a pivoted door on said casing, an auxiliary shaft mounted on and extending through 25 said door and means on said shafts adapted to interlock when the door is closed so that the shaft within the casing may be driven from outside the casing by turning the auxiliary shaft.

2. In combination a casing of a motion picture apparatus, a rotatable shaft disposed therein, means on either end of said shaft for turning it, one end of said shaft being disposed within the casing, the other end 35 disposed outside the casing, a pivoted door on said casing disposed when closed adjacent the end of the shaft within the casing, an auxiliary shaft mounted on and extending through the door, means on said auxiliary 40 shaft outside the door for turning it, and means on the adjacent ends of the main and auxiliary shaft to interlock when the door is closed to permit the main shaft to be turned by manipulating the outer end of 45 the auxiliary shaft.

3. In combination a casing of a motion picture projector, a framing shaft disposed therein for rotation, one end of said framing shaft disposed within the casing, the other 50 end disposed outside the casing and a knob on said latter end, a pivoted door on said casing disposed when closed adjacent the end of the framing shaft within the casing, an auxiliary shaft mounted on and extending through said door, a hand knob on the inner end of the main shaft, a hand knob on the outer end of the auxiliary shaft and means on the adjacent ends of said shafts adapted to interlock when the door is closed 55 to permit the operation of the framing shaft by the turning of the hand knob on the outer end of the auxiliary shaft.

4. In combination a casing, a shaft disposed therewithin, a pivoted door on said 60 casing, an auxiliary shaft mounted on and

extending through said door, and a series of cooperating pins and recesses on adjacent ends of said shafts adapted to interlock when the door is closed to permit the one shaft to operate the other.

70

5. In combination a casing, a shaft disposed therewithin, a pivoted door on said casing, an auxiliary shaft mounted on and extending through said door, a series of spaced pins associated with the inner end 75 of the auxiliary shaft, the adjacent end of the main shaft within the casing having associated therewith a series of spaced holes or recesses adapted to receive said pins when the door is closed whereby the main shaft 80 may be operated by the auxiliary shaft.

6. In combination a casing, a rotatable shaft disposed transversely therein, one end of the shaft disposed outside the casing, a hand knob thereon, the other end of the 85 shaft disposed within the casing a hand knob thereon, said latter hand knob having a plurality of spaced recesses thereon, a pivoted door on the casing disposed when closed adjacent the inner end of said shaft, an auxiliary shaft mounted on and extending through said door, a hand knob on the outer end of said shaft, the hand knob on the inner end of the first mentioned shaft having a plurality of recesses thereon, and a plurality 90 of spaced pins on the inner end of the auxiliary shaft to interlock the said recesses when the door is closed to permit the manipulation of the shaft within the casing by the auxiliary shaft from without the casing.

95

In testimony whereof we have hereunto set our hands.

ALBERT KINDELmann.
EWALD BOECKING.
